G. S. ROGERS,
NON-REFILLABLE BOTTLE,
APPLICATION FILED FEB. 10, 1915.

1,170,108.

Patented Feb. 1, 1916.

UNITED STATES PATENT OFFICE.

GEORGE S. ROGERS, OF PANA, ILLINOIS.

NON-REFILLABLE BOTTLE.

1,170,108.

Specification of Letters Patent.

Patented Feb. 1, 1916.

Application filed February 10, 1915. Serial No. 7,305.

To all whom it may concern:

Be it known that I, GEORGE S. ROGERS, a citizen of the United States, residing at Pana, in the county of Christian and State 5 of Illinois, have invented certain new and useful Improvements in Non-Refillable Bottles, of which the following is a specification.

This invention relates to bottle stoppers, 10 and more particularly to that class of bottle stoppers which are designed to permit initial filling of a bottle, but which will effectually prevent refilling of the same upon dispensing of the original contents thereof.

An object of the invention is to provide a 15 bottle having a groove in the neck thereof, and to provide a stopper having a spring disposed thereabout and adapted to engage the groove of the bottle neck to lock the stopper within the neck.

Another object is to provide a plurality 20 of gaskets to prevent the liquid contained within the bottle from coming in contact with the metal spring.

A further object is to provide a valve seat 25 within the stopper and to mount the valve therein, means being disposed at the upper end of the stopper to prevent the valve from becoming disengaged from the stopper and 30 to prevent tampering with the valve.

With these and other objects in view the invention consists in the novel features of construction, combination and arrangement of parts as will be hereinafter more fully 35 described, illustrated in the accompanying drawings and claimed.

In the drawings:—Figure 1 is a vertical 40 sectional view through a bottle neck showing the improved stopper mounted therein; Fig. 2 is a section on the line 2—2 of Fig. 1; Fig. 3 is a section on the line 3—3 of Fig. 1; Fig. 4 is a side elevation of the stopper removed.

Referring to the drawings by numerals, 1 45 designates a bottle which is provided with the usual neck 2, the bore thereof being tapered inwardly from its upper end to its point of communication with the bottle proper, an annular groove 3 being formed 50 in the neck for a purpose which will presently appear.

A stopper 4, preferably constructed of 55 glass, is adapted to be mounted within the neck of the bottle and prevented from becoming disengaged therewith by means of an expandible ring 5 which engages between

an annular groove 6 formed in the stopper and the groove 3. This spring is adapted to be forced within the groove 6 of the stopper 4 upon entering the stopper within the 60 bottle neck and is adapted to spring into engagement with the groove 3 when the groove 6 becomes alined therewith.

In order to prevent the contents of the bottle from coming in contact with the 65 spring 5, the upper and lower portions of the stopper have gaskets 7 extending therearound, shoulders 8 being formed on the stopper in order to prevent the gaskets from becoming disengaged therewith during the 70 operation of inserting the stopper within the neck.

The interior of the stopper 4 is recessed, 75 as shown at 9, and into this recess is adapted to be placed a ball valve 10, this valve being preferably formed of glass and adapted to engage a seat formed in the lower portion of the recess 9 in order to prevent liquid from being poured into the bottle after the stopper has been applied thereto.

A plurality of guard members 11 are 80 formed upon the upper face of the stopper 4 and are adapted to be bent into substantially semicircular shape thereover in order to prevent tampering with the valve and to 85 form a means to limit the outward movement thereof. These members 11 are formed of different lengths and are adapted to be bent one upon the other in order to provide spaces 12 therebetween to form a 90 means of exit for the contents of the bottle when the same is inverted to pour the contents therefrom when the same is tilted. The valve may be inserted within the recesses during the operation of forming the 95 stopper while the members 11 are in a malleable condition and the members 11 then bent to their final position. This construction positively prevents tampering with the valve 10 after the stopper has been applied 100 to the bottle neck.

From the foregoing description taken in connection with the accompanying drawings it is thought that the construction and operation of the device will be clearly understood and while I have herein shown and described one specific form of my invention I do not wish to be limited thereto except for such limitations as the claims may import.

What is claimed is:—

In combination with a bottle having an

annular groove formed in the neck thereof, of a stopper having an annular groove formed therein, a split ring engageable with said groove to retain said stopper in position within said neck, a plurality of gaskets carried by said stopper and engageable with the inner surface of said neck to prevent the contents of the bottle from coming into contact with said ring, said stopper being cut out to form a valve seat, a valve in said cut-out normally resting on said seat, a plurality of guard members having their one end fixed to said stopper, said guard

members being formed of a non-resilient material and arranged so that they extend 15 upwardly at an angle to meet and overlap at their upper ends, and said guard members being so spaced apart to permit the free flow of fluid therebetween substantially as described.

In testimony whereof I affix my signature in presence of two witnesses.

GEORGE S. ROGERS.
